UNITED STATES PATENT OFFICE.

CHARLES E. FRYE, OF FLORA, INDIANA.

SWITCH.

No. 858,276.

Specification of Letters Patent.

Patented June 25, 1907.

Application filed August 22, 1906. Serial No. 331,680.

To all whom it may concern:

Be it known that I, CHARLES E. FRYE, a citizen of the United States, residing at Flora, in the county of Carroll and State of Indiana, have invented new and useful Improvements in Switches, of which the following is a specification.

The invention relates to an improvement in switch operating mechanism, designed primarily for use with street railway switches.

The main object of the invention is the provision of means whereby the mechanism is arranged for manual control by the car operator, and under such control may be used to operate the switch in either direction.

The preferred details of construction will be described in the following specification, reference being had particularly to the accompanying drawings, in which:

Figure 1 is a plan of a section of car track illustrating the application of my invention, the car and operating means carried thereby being shown in dotted outline, Fig. 2 is a vertical section of the same, the car being broken away, Fig. 3 is a transverse section through the track rails, illustrating the connection of the switch rod to the switch point.

Referring particularly to the drawings, wherein similar reference numerals indicate like parts throughout the several views, 1 represents track rails, and 2 the usual switch point arranged for co-operation with one of the rails, said point being pivotally supported on the usual wear plate 3.

A shifting lever 4 is pivotally supported between the rails 1 in advance of the switch point, said lever being preferably pivoted at a point intermediate its length upon a wear plate 5 secured to the underlying tie, end

wear plates 6 being disposed to underlie the respective ends of the lever to insure proper movement of the latter. The relatively rear or switch controlling end of the lever is connected to the switch point through the medium of an operating rod 7, the connection of said rod and switch point being of a relatively yielding character. The described connection is secured by passing said rod through the switch point and through an

opening 8 in the web of the rail, and arranging coil springs 9 to encircle the rod on opposite sides of the switch point, and bear between said point and fixed stops 10 on the rod. By this connection the movement of the rod is transmitted to the switch point through the medium of the springs 9, where-

by a yielding connection is provided at this point of such character as to insure the operation of the switch point under the influence of the rod when said point is free to move, while at the same time permitting an independent movement of the rod in the event the switch point should be immovable through the accumulation of foreign material between said point and rail.

The relatively forward or car controlling end of the lever is provided with an upwardly extending post or standard 11, preferably of angular shape in cross section with the forward apex or edge of the post in alignment with the longitudinal center of the lever 4. The standard 11 is of such length as to project above the road bed of the track to permit the hereinafter described operation by the car, the angular arrangement of the standard assisting in the car operation while at the same time reducing to a minimum the danger of a breakage of the post through contact with the wheel of a passing vehicle, as the inclined sides of the post will obviate a direct impact of such wheel and post.

The car operating means comprises parallel rods 12 projecting through the platform of a car, as 13, and formed on their upper ends with a tread disk 14. The lower ends of the rods 12 are slidably mounted in the hanger 15 supported beneath the car, and are held in normal, or retracted position through the medium of coil springs 16 encircling each rod and bearing between the hanger and a cross pin 17 carried by the rod. Beyond the cross bar of the hanger 15 the rods 12 are provided with operating disks 18, mounted on the rod for free rotation and secured thereon by nuts 19 or other fastening means.

The rods 12 are arranged in the platform on either side of the line thereof coincident with the post 11 of the lever, the disks 18 being of such diameter as, when depressed into operative position, to engage the post 11 and swing the relatively forward end of the lever in one direction or the other as the car advances. The springs 16 are so disposed as to normally support the disks 18 above the plane of the upper end of the post 11, as clearly shown in Fig. 2, so that the operator may, by depressing the desired rod 12, operate the switch point in the desired direction.

The relatively forward wear plate 6 is provided with a lever guiding member 20, arranged in advance of the post 11. The guiding member is substantially of staple form,

the cross bar overlying the end of the lever in advance of the post and the points of the member being passed through the wear plate and into the underlying tie, as clearly shown in Fig. 2.

The use of the spring 9 forms an important part of the present invention, as thereby operation of the lever 4 by the car is permitted even if the switch point is incapable of movement through obstruction. Furthermore, any undue lateral swaying of the car while engaging the post 11 during travel of the car, is compensated for, and the rigid parts of the structure thereby secured against undue strain or breakage. Such swaying of the car would, of course, have a tendency to move the post a distance in excess of the normal movement, which excess movement, if not compensated for would have a tendency to break some one or more of the connections. The spring connection entirely obviates this difficulty, and permits the normal movement of the switch point under all possible conditions. The lever 4, rod 5, and connections thereof to the switch point are supported directly upon the tie structure, being in the event of railway bed construction for the streets of cities, concealed in any desirable form of casing having a removable cover to permit access to the working parts.

From the construction described it will be

obvious that the car operator may, by controlling the particular rod 12 desired, operate the switch in either direction without the necessity of stopping the car.

35

Having thus described the invention, what I claim is:—

In combination with the point of a switch, of a lever suitably pivoted to a wear plate intermediate its length, a rod pivoted to one end of the lever and being in yielding engagement with the point, said rod being provided with a coil spring encircling the same and a fixed stop at the end and intermediate the length of the rod, said stop holding the spring in operative position, said spring passing through an opening in the switch point and through an opening in the web of the rail, a post angular in cross section projecting upwardly from the lever and positioned adjacent the opposite end thereof, and a guiding member for the lever arranged thereabove, said member being suitably secured at both sides of the lever and limiting the movement thereof.

55

In testimony whereof, I affix my signature in presence of two witnesses.

CHARLES E. FRYE.
